UNITED STATES PATENT OFFICE

JAMES W. BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK

TIME RECORDER

Application filed June 30, 1926. Serial No. 119,584.

This invention relates to improvements in time recorders and is directed to general improvements in that class of recorders known as card recorders. It is primarily concerned with the spring motor drive of the various time controlled units of a recorder and in mechanism which is designed to automatically maintain the motor spring wound during an extended period of time of continuous usage of a recorder. Heretofore, devices designed to accomplish this purpose have been suggested, but they have embodied the use of such impositive devices as friction clutches which, by reason thereof, may be considered to have fallen short of reaching the present objective. Such impositive devices by reason of their very nature are objectionable because of the unutilized amount of energy that must be put into them in order to make a friction transmission of energy possible. Accordingly, it is an object of my invention to provide suitable means by which a workman will introduce an increment of energy into a spring motor upon every operation of the recorder lever until the spring motor is wound to a predetermined limit, at which limit the recorder lever will automatically become ineffective for further rewinding. A further object resides in providing, in a mechanism adapted to perform the object primarily stated, an automatic arrangement which will prevent the rewinding operation of the motor springs by the recorder lever until the stored energy has dropped below a predetermined limit. When the stored energy of the motor springs drops to this last named limit, rewinding by the recorder lever will be rendered again possible. The rewinding connections intermediate the recording lever and the motor springs are of a positive nature which are adapted to be disassociated automatically when the motor springs have been wound by the repeated operations of the recording lever to a definite limit, which limit may be exceeded through the instrumentality of winding keys. In any event, no rewinding energy may be introduced through the recording lever before the energy of the motor springs has dropped to the lower limit.

This feature and others will be described fully in the specification and illustrated in the drawings, in which:

Fig. 1 is a view of the spring motor and connections as seen from the right side of a time recorder,

Fig. 1A is a detail of the rewind actuating pawl as seen on line 1A—1A of Fig. 1,

Fig. 2 is a front elevation on line II—II of Fig. 1,

Fig. 3 is a detail of the controlling mechanism for rendering effective the recording lever for rewinding the motor springs, and

Fig. 4 illustrates the position of the controlling mechanism when the recording lever is ineffective for rewinding of the motor springs.

Referring to Figs. 1 and 2, 1 designates a box frame forming the main support of the entire mechanism and is adapted to be secured to a wall by means of screws. In the lower portion thereof, there is disposed a power drive for the clock and recorder which is readily removable. The front of the box frame is open except at the lower portion and for an intermediate frame 2 to which the cover 3 and the recording unit are secured. The clock mechanism is located to the rear of frame 2. Cover 3 fits tightly against edge 5 of box frame 1, and, taken together with the box frame, comprises a complete dustproof container for all of the mechanism of a time recorder.

Only such parts of the recording mechanism as are necessary to understand the present invention are disclosed herein, and reference may be had to the application of Clinton E. Larrabee, Serial No. 3574, filed January 20, 1925, for further disclosure.

The means for driving the recording and clock mechanisms consists of an independently mounted unit held together by four tie rods 6 and two side plates 7 which are fastened in place to the box frame by screws 8.

Between side plates 7 there is freely mounted shaft 9 upon which are loosely mounted gears 10 and 11 and spring barrels 12 and 13 fastened respectively to gears 10 and 11. Each spring barrel encloses a spring 14 wound in opposite directions about shaft 9.

with their outer ends staked to the barrels and with their inner ends staked to the shaft. Gear 10 is the winding gear and is actuated by pinion 15 on shaft 16 having at its right end lugs for the purpose of affixing a crank handle. The rotation of shaft 16 in a winding operation in a counterclockwise direction, Fig. 1, causes a tightening of the right hand spring, Fig. 2, which transmits its tension through shaft 9 to the left hand spring 14 in barrel 13, this barrel being nearly motionless when gear 11 is actuating the clock. When the springs are wound, retrograde motion of gear 10 is prevented by spring pressed pawl 17, Fig. 1, bearing against ratchet wheel 18 fixed to shaft 16.

It is advantageous that the spring motor be kept wound at all times and this is accomplished by rewinding it to a slight extent on each operation of the operating lever 19. To the operating lever pivot there is secured an arm 20 swingingly supporting link 21 which connects it with lever 22. The lower end of this lever has pinned thereto, so that it can be readily unfastened, a link 23, one end of which is connected to an arm 24 pivotally supported on shaft 16. Arm 24 has pivoted thereon a member 25 and ratchet 26 which are fastened together by screw 27 when they have been properly adjusted. This member and ratchet are free to rotate together about pivot 28 except for the frictional resistance offered by spring 29 (Fig. 1A) which tends to hold them in the position where they were last left. This position is dependent upon the position of wishbone member 30 pivoted at 31 and having two studs 32, 33 capable of bearing against adjacent flat surfaces on member 25. If the wishbone is held in the position shown in Fig. 1 ratchet 26 will actuate ratchet wheel 18 on each operation of the operating lever 19. However, when the springs are sufficiently wound it is desirable to throw out the winding ratchet and this is accomplished by rotating wishbone 30 clockwise about pivot 31 so that stud 33 will force the lower end of member 25 forward.

The position of the wishbone is under the control of the condition of the spring motor and this condition is communicated through the snap action mechanism shown in Figs. 3 and 4. This mechanism comprises a slide 34 having ears 35, by which it is supported for sliding movement on rod 36. At the right hand end of the slide there is, adjustably fastened by two set screws 51, a plate 37 having therein a cam slot 38 for controlling the position of member 30. For this purpose the rear end of member 30 carries a stud 39 to engage within the cam slot. Slide 34 is kept from swinging by means of bracket 40 having a headed stud 41 passing through slots in the slide and cam plate 37.

The slide has two limiting lugs 42, 43, of

sufficient length to be contacted by nut gear 44 in its travel on screw 45 (Fig. 2). Screw 45 is left handed and is on the outer surface of a sleeve which is pinned to shaft 46 and rotates therewith when driven by gear 11 through pinion 47, which is likewise fixed to shaft 46. As the spring motor unwinds, shaft 46 will be rotated counterclockwise (Fig. 1) and nut 44 will travel to the right. In its travel to the right, it will contact lug 43 and move slide 34 along with it. As slide 34 approaches the approximate middle of its longitudinal travel, wedge-shaped stud 48 will come against the slanting face of pawl 49 and cam the pawl in a clockwise direction against the action of spring 50 until the top of the stud passes the point of the pawl. At this instant the restraining force on spring 50 is eliminated and the spring will act to snap the slide to the right (Fig. 3), with the result that cam slot 38 raises the rear end of wishbone member 30 and stud 32 thereon rocks member 25 and ratchet 26 counterclockwise to the position shown in Fig. 1.

In this position, ratchet wheel 18 will be actuated on every depression of operating lever 19, and gear 10 will be advanced in the direction of the arrow to wind the spring motor. As the spring motor is gradually rewound, gear 10 will rotate nut 44 counterclockwise and cause it to travel to the left on the nearly non-rotating screw 45. Nut 44 will contact stud 42 and carry slide 34 to the left, as shown in Fig. 3, to the position where pawl 49 will be displaced to its maximum extent and then suddenly snap the slide to the left, as seen in Fig. 4. This snap action causes ratchet 26 to be suddenly disengaged from contact with ratchet wheel 18 and thus throw out the step-by-step automatic rewind of the operating lever 19.

The disengagement is obtained through the lowering of the rear end of wishbone member 30 when stud 39 is cammed downwardly thus causing member 25 to be positioned in its non-functioning position as described above. Set screws 51 are provided to adjust the timing relation between the snap action and ratchet positioning.

Power from the spring motor is distributed to the clock and recorder mechanisms by means of gear 11 and through the intervention of pinion 52 and gear 53, both fixed to shaft 54 (Fig. 1). Gear 53 meshes directly with pinion 55 on shaft 56 which also carries beveled gear 57 fixed thereto. Beveled gear 57 meshes with another beveled gear 58 on the lower end of short shaft 59. This short shaft is mounted in a bracket 60 fastened to the left hand plate 7 and carries at its upper end a universal socket 61 for the reception of the lower end of a universal shaft 62. This connection is readily severed as is also the connection between lever 22 and link 23 in

order that the entire spring motor mechanism can be removed as a unit.

Shaft 62 is driven in a clockwise direction as seen from above, and its upper end rotates a short shaft (not shown) which is connected to shaft 62 in such a manner as to bear the same relation to shaft 62 as short shaft 59 bears to shaft 62. Shaft 62 transmits energy from the motor springs to the clock mechanism and time controlling mechanism which in turn controls the operation of the various instrumentalities of a time recorder. Shaft 63 is driven from the time controlling mechanism through shaft 64 and gear 65 on shaft 63. Fixed to the forward end of shaft 63 is a gear 66 which concurrently drives, through shaft 67, the time indicating mechanism, generally designated as 68, and type wheels of the recorder assembly, generally designated as 69. The details of these assembly units may be of any well known type.

I claim:

1. In a recording apparatus, the combination comprising a manipulative member, a spring motor, means for storing energy in said spring motor upon actuation of said manipulative member, said means including a ratchet and ratchet wheel, means for positioning said ratchet to engage or not engage said ratchet wheel, and means controlled by said spring motor for controlling the operation of said last named means.

2. In a recording apparatus, the combination comprising a manipulative member, a spring motor including a plurality of barrels and a plurality of springs secured to said barrels, a gear secured to each of said barrels, means actuated by said manipulative member to rotate one of said barrels through its gear and to energize said spring motor, and means controlled by said last named barrel to render said means ineffective for winding said spring motor beyond a predetermined limit.

3. In a recording apparatus, the combination comprising a manipulative member, a spring motor, a plurality of barrels, a plurality of springs secured to said barrels, means actuated by said manipulative member to rotate one of said barrels and to energize said spring motor, and means controlled by another of said barrels to render said means effective to wind said spring motor.

4. In a recording apparatus, the combination comprising a manipulative member, a spring motor comprising a plurality of barrels and a plurality of springs secured to said barrels, means actuated by said manipulative member for energizing said spring motor through one of the barrels, a screw rotated by said spring motor through another barrel as energy of said spring motor is being utilized, a gear nut threaded upon said screw, a gear on the first mentioned barrel for rotating said nut, and means controlled

by the position of said gear nut upon said screw for rendering said first named means effective to energize said spring motor upon actuation of said manipulative member and to render said first named means ineffective when said spring motor has been wound to a predetermined limit.

5. In a recording apparatus, the combination comprising a manipulative member, a spring motor, a ratchet and ratchet wheel, connections intermediate said ratchet and said manipulative member, means for positioning said ratchet for engaging said ratchet wheel, a winding gear for said spring motor, and means controlled by said winding gear for positioning said first named means so as to prevent said ratchet from engaging said ratchet wheel whereby actuation of said manipulative member will be ineffective to operate said winding gear.

6. In a recording apparatus, the combination comprising a manipulative member, a spring motor, a ratchet and ratchet wheel, connections intermediate said ratchet and said manipulative member, means for positioning said ratchet for disengaging said ratchet wheel, a winding gear for said spring motor, a gear operated by said spring motor, and means controlled by said gear for positioning said first named means so as to cause said ratchet to engage said ratchet wheel whereby actuation of said manipulative member will be effective to operate said winding gear.

7. In a recording apparatus having type wheels and a spring motor for driving the same, the combination comprising a manipulative means for rewinding said spring motor on each operation thereof, positive connections intermediate said manipulative means and said spring motor including a ratchet and ratchet-wheel, and means to automatically prevent said ratchet from engaging said ratchet wheel when said spring motor has been wound to a predetermined limit.

8. In a recording apparatus, the combination of spring driven means, a spring motor having a plurality of springs and a plurality of barrels, each barrel being fastened to a spring and the springs being operatively secured together at their ends which are remote from the barrel spring fastenings, a gear mounted upon one of said barrels for transmitting energy from said spring motor to said spring driven means, a second gear mounted upon another of said barrels, actuating means for rotating said second gear when energy is being introduced into said spring motor, and means controlled by said first mentioned gear for rendering said actuating means ineffective.

9. In a recording apparatus, the combination of spring driven means, a spring motor having a plurality of springs and a plu-

rality of barrels, each barrel being fastened to a spring and the springs being operatively secured together at their ends which are remote from the barrel spring fastenings, a 5 gear mounted upon one of said barrels for transmitting energy from said spring motor to said spring driven means, a second gear mounted upon another of said barrels, actuating means for rotating said second gear 10 when energy is being introduced into said spring motor, and means controlled by both of said gears for controlling the engagement of said actuating means.

10. In a recording apparatus, the combination of spring driven means, a spring motor having a plurality of springs and a plurality of barrels, each barrel being fastened to a spring and the springs being operatively secured together at their ends which are remote from the barrel spring fastenings, a 15 gear mounted upon one of said barrels for transmitting energy from said spring motor to said spring driven means, a second gear mounted upon another of said barrels, actuating means for rotating said second gear 20 when energy is being introduced into said spring motor, and means controlled by said second named gear for disengaging said actuating means.

30 In testimony whereof I hereto affix my signature.

JAMES W. BRYCE.
